MAGNETOELECTRIC PICK-UP DEVICE FOR
STRINGED MUSICAL INSTRUMENTSHerbert S. Sunshine, New York, N. Y., assignor
to Epiphone, Inc., New York, N. Y., a corpora-
tion of New York

Application November 10, 1937, Serial No. 173,758

2 Claims. (CL 84—1.16)

The present invention relates to stringed musical instruments such as the guitar, banjo, mandolin and the like, and more particularly to a magneto-electric pick-up device adapted to be incorporated in such musical instruments whereby the vibrations of the strings are translated into a pulsating electric current which is amplified and transformed into sounds corresponding in pitch and quality to the sounds produced by the vibrations of the strings.

The principal object of the present invention is to provide in a stringed musical instrument, an improved type of magneto-electric pick-up unit which will faithfully and accurately reproduce the characteristic tones of the instrument. Another object of the invention is to provide in a stringed musical instrument, a pick-up unit which is adjustable for each string of the instrument. A further object of the invention is to provide in a stringed musical instrument having strings of different diameters, a pick-up unit including a plurality of individually adjustable core-members adjacent respective strings which are adapted for adjusting the air gaps therebetween, to compensate for the ordinary spacing variation which is due to the difference in the diameters of the strings. A still further object of the invention is to provide in a stringed musical instrument a magneto-electric pick-up unit of the character described, which is simple in construction, economical to manufacture and efficient in use. Other objects and advantages of the present invention will in part be pointed out hereinafter and will in part be apparent to those skilled in the art to which the present invention relates.

With the above and other objects in view, the present invention consists of the novel features of construction and arrangement of parts hereinabove set forth and illustrated in the accompanying drawing wherein there is shown the preferred embodiment of my invention.

In the accompanying drawing which forms an integral part of this specification,

Fig. 1 is a top plan view of the body portion of a stringed musical instrument showing the embodiment of my invention together with an amplifying circuit associated therewith;

Fig. 2 is an enlarged sectional view of the instrument taken on the line 2—2 of Fig. 3; and

Fig. 3 is an enlarged fragmentary sectional view of the instrument taken on the line 3—3 of Fig. 1.

Referring now to the drawing wherein like reference characters indicate corresponding

parts throughout the several views 10 represents the body of the instrument which preferably has a hollow interior and which may be made in any desired shape or size. The body 10 is preferably constructed of non-resonant material such as metal or hard wood of substantial thickness, for the present invention contemplates the reproduction of the tones produced solely by the vibrations of the strings without any resonant effects which may be produced by the body 10 of the instrument. Extending from the body 10, in the conventional manner, is the neck of the instrument 11 which may be attached to the body or may be constructed integral therewith. The upper side of the neck 11 forms a fingerboard 15 which is provided with spaced frets 12. Strings 13, which are preferably made of magnetic material and which are, in the conventional practice, of unequal diameters, are tensioned over the body and neck of the instrument in parallel arrangement, and lie in substantially a common plane. The strings 13 pass over a bridge 14 which is secured to the upper side of the body 10 and is situated toward the outer end thereof, and over a similar bridge (not shown) on the fingerboard, situated near the outer end of the neck 11. The strings 13 are secured at one end to a tail-piece 15 and at the other end they are engaged by keys or pegs (not shown) which are adapted for tensioning of the strings. The strings are in this manner adapted to be manually plucked or otherwise manipulated by the player to produce the desired vibrations.

The pick-up unit which is designated in general by numeral 16, comprises a permanent magnet 17 of U-shape or horse-shoe design. Mounted over one of the poles of the magnet 17 is an angular plate 18 which is constructed of magnetic material having a lesser degree of hardness than the magnet 17 to make it adaptable for tapping in order to receive the threaded core-members which will be referred to hereinafter. The magnet 17 and the angular pole-plate 18 are together attached to an elongated supporting bar or bracket 19 by means of suitable studs or bolts 20. The pick-up unit is mounted within the interior of the body 10 by means of suitable studs or bolts 21 which project upwardly from the ends of the supporting bar or bracket 19 and extend through openings in the upper side of the body. Nuts 22 are threaded over the outer ends of the bolts 21 for securing the unit 16 to the upper side of the body.

The pick-up unit includes a plurality of core-members 23 of magnetic material which are

threaded into the pole-plate 18 and project upwardly, the upper ends being spaced directly below the strings 13 as illustrated in Figs. 2 and 3 of the drawing. The core-members 23 are threaded into the pole-plate 18 to permit of their adjustment relative to the strings in order to obtain the proper spacing therebetween, and are preferably provided with screw heads 24 so that they may be readily adjusted with a screw-driver.

10 The pick-up unit also includes a coil 25 of suitable wire which is preferably wound on a spool 26 formed of suitable insulating material. The spool 26 is adapted to be supported on the pole-plate 18 and surrounds the core-members 23, in such manner that the outer ends of the core-members project slightly above the outer side of the spool. The coil 25 is electrically connected to a suitable amplifier and loud-speaker unit 27 by means of conductors 28 connecting the coil 25 to a jack 29 provided in the body, which is adapted to receive conductors extending from the amplifying unit 27. A variable resistance volume control 30 and a tone control 31 may be provided in the instrument and interposed between the coil and amplifying unit, including respective control knobs 32 and 33 which project from the upper side of the instrument to make them conveniently accessible for manipulation by the player.

30 The underside or bottom of the body 16 is provided with an opening whereby to permit insertion of the pick-up unit 16 for mounting within the body. This opening is normally covered by a closure plate 34 which may be attached to the body in any suitable manner. The upper side of the body 16 is also provided with an opening 35 positioned underneath the strings 13 and extending transversely thereof. The opening 35 permits the upper portion of the pick-up unit 16 to extend therethrough.

In the operation of the instrument, the strings 13 being adjacent the magnet 17, are magnetized thereby. When set in vibration by the player, the magnetized strings induce a pulsating current in the coil 25, which is amplified and transformed by the amplifier and loud-speaker unit 27 into tones corresponding to those produced by the vibrations of the strings. To increase the induction within the coil, the coil is generally provided with a core and the electromotive force which is induced in the coil by the vibrations of the strings varies with the spacing between the strings and the core. The strings of the instrument being conventionally of different diameters 55 and lying in a common plane would ordinarily provide air gaps between the strings and core which would vary with the diameters of the strings. To compensate for this difference in spacing, the core of my present invention consists of a plurality of core-members 23 which are threaded into the pole-plate 18 of the magnet 17 each core-member having its outer end facing

one of the strings of the instrument. In this manner the core-members 23 are rendered adjustable for spacing relative to the strings to provide for the required air gap between each string and its respective core-member. The screw heads 24 on each of the core-members enables them to be readily raised or lowered with a screw-driver. The adjustability of the core-members also permits any desired variation in the air gap between each string and its corresponding core-member to either increase or decrease the pick-up effect. The instrument may thus be voiced to produce desired tone-effects. It will thus be observed that by means of the present invention the player may readily obtain the proper balance in the pick of the strings and the musical tuning or notation of his choice with a minimum of effort.

Having described and illustrated the preferred embodiment of my invention, I desire to be understood that I do not wish to limit myself to the specific form of my invention herein set forth, for it will be apparent to those skilled in the art that variations may be made in the details of construction which will nevertheless fall within the scope of my invention as defined in the appended claims.

Having thus described and illustrated my invention, what I claim as new and desire to secure by Letters Patent is:

1. A pick-up unit for use in a stringed musical instrument having a plurality of vibratory strings, comprising a permanent magnet having the end portion of one of its pole-portions disposed transversely of the strings, a plate mounted on said pole portion of the magnet, said pole plate having a plurality of spaced threaded holes therein, a plurality of threaded core-members adjustably positioned in said holes, each core-member having a face adjacent one of the strings and being individually adjustable for spacing relative thereto, and an induction coil supported by said pole-plate and surrounding said core-members.

2. A pick-up unit for use in a stringed musical instrument having a plurality of vibratory strings comprising a permanent magnet generally U-shaped in cross section, a plate mounted on a pole-portion of the magnet, a pole plate having a plurality of spaced, threaded holes therein, a plurality of threaded core members adjustably positioned in said holes, an induction coil supported by the pole plate and surrounding the several core members, and means for supporting the magnet, plate, core members and coil as a unit beneath the general plane occupied by the strings of the stringed instrument with the poles of the magnet directed upwardly towards and transversely of the strings, and with the several core members being respectively disposed adjacent to and in general alignment with the strings.

HERBERT S. SUNSHINE.
